HOOP ROLLING DEVICE

Virgil K. Rath, 112 S. Pearl St., Janesville, Wis. 53545

Filed Dec. 14, 1970, Ser. No. 26,482

Term of patent 14 years

Int. Cl. D21—01

U.S. Cl. D34—5

FIG. 1 is an isometric view of a hoop rolling device embodying my new design;

FIG. 2 is a front elevation view of my hoop rolling device; and

FIG. 3 is a side elevational view of my hoop rolling device, the other side being identical.

I claim:

The ornamental design for a hoop rolling device, as shown and described.
